Atty

UNITED STATES PATENT OFFICE.

ROBERT G. CAMBLIN, OF BARTLESVILLE, OKLAHOMA, ASSIGNOR OF ONE-HALF TO
ANTHONY R. EDMONDSON, OF BARTLESVILLE, OKLAHOMA.

CUT-OFF VALVE.

Application filed March 24, 1923. Serial No. 627,380.

To all whom it may concern:

Be it known that I, ROBERT G. CAMBLIN, a citizen of the United States, residing at Bartlesville, in the county of Washington 5 and State of Oklahoma, have invented certain new and useful Improvements in Cut-Off Valves, of which the following is a specification, reference being had to the accompanying drawings.

This invention relates to certain improvements in cut off valves and has relation more particularly to a device of this general character adapted to be interposed in a gas line and it is an object of the invention to 15 provide a novel and improved device of this general character which automatically cuts off the flow of gas when the pressure drops below a predetermined degree.

It is also an object of the invention to 20 provide a novel and improved device of this general character wherein the valve is normally maintained in open position under the influence of the pressure of the gas and which moves into closed position upon reduction of such pressure and wherein means is provided to prevent the valve from returning to open position under the influence of the pressure of the gas.

The invention consists in the details of 30 construction and in the combination and arrangement of the several parts of my improved cut off valve whereby certain important advantages are attained and the device rendered simpler, less expensive and 35 otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:—

Figure 1 is a view in perspective with a 45 portion broken away of a cut off valve constructed in accordance with an embodiment of my invention;

Figure 2 is a vertical sectional view taken 50 through the device as illustrated in Figure 1 with certain of the parts in elevation.

As disclosed in the accompanying drawings, P denotes a pipe line leading to a

burner of a gas stove or the like and which is in communication with the cylinder C. The cylinder C is suitably coupled to a main 55 pipe M.

The cylinder C is vertically disposed and has mounted therein for rectilinear movement the valve V secured to the lower or inserted end portion of the stem or rod 1. The rod 1 has free sliding movement 60 through the bonnet or cap 2 herein disclosed as in threaded engagement with the upper end portion of the cylinder C. The normal pressure of the gas flowing from the main line M of the pipe P is sufficient to maintain the valve V in a raised or open position but when such pressure decreases the valve V moves downwardly under the influence of the weight W so that when such decreasing pressure reaches the danger point 65 the valve V will have moved into closed position or into such position to prevent the flow of the gas into the pipe P. The weight W as herein disclosed is freely mounted on the stem or rod 1 and is supported by a cross pin 3 disposed at desired points through the 70 stem or rod 1.

Extending outwardly from the upper portion of the cylinder C is an arm 4 having 80 its outer end bifurcated and extending from above within the kerf 5 of said bifurcation is the lower end portion of an arm 6 comprised in the latch L. The intermediate portion of the latch L is inwardly offset as at 7 while the upper portion of the latch comprises a grooved arm 8 to snugly engage the stem or rod 1. The lower portion of the arm 8 at opposite sides thereof is cut away to provide the downwardly facing 85 stop shoulders 9 which, when the latch L is in engagement with the rod or stem 1, overlies a cross pin 10 carried by the stem or rod 1 and disposed therethrough and whereby the rod or stem 1 is effectively locked 90 against upward movement.

The pivoted end portion of the arm 6 is provided with a slot 11 to provide a supplemental arm 12 and encircling the arm 12 and interposed between the face of said slot 100 and the arm 5 is a coil spring 14. This spring 14 serves to constantly urge the latch L toward the stem or rod 1.

The shoulders 9 hereinbefore referred to

are so positioned that when the valve V has moved into closed position the same will overlie the pin 10 and thereby effectively hold the valve V against upward or opening movement when the pressure of the gas increases.

Supported upon the cylinder C is a housing or cap H, the top of said housing or cap being provided with an opening 15 through 10 which the rod or stem 1 is freely movable. This housing or cap H covers the weight W and the latch L. The walls of the housing or cap H at diametrically opposed points are provided with longitudinally disposed 15 slots 16 through which extend the extremities of the pin 10 hereinbefore referred to whereby said housing or cap H serves as a guide for the rod or stem 1, holding said rod or stem against turning and thereby 20 maintaining the pin 10 at all times in a position for proper coaction with the latch L. Extending outwardly from the upper portion of the cylinder C are the pins 17 which also extend within the slots 16 whereby the 25 housing or cap H is maintained against turning with respect to the cylinder C.

The wall of the housing or cap H at a predetermined point thereon is provided with an opening 18 through which extends 30 a pin 19 or the like operatively engaged with the latch L whereby the latch L may be readily swung into an inoperative or release position without the necessity of removing the housing or cap H.

35 The communication between the cylinder C and the pipe P as herein disclosed is by means of the relatively small openings 20 drilled through a wall of the cylinder C inwardly and downwardly on an angle of approximately 45°. This arrangement is provided so that it will be assured no hindrance or obstruction will be offered to the valve V during its closing movement.

45 From the foregoing description it is thought to be obvious that a cut off valve constructed in accordance with my invention is particularly well adapted for use by reason of the convenience and facility with which it may be assembled and operated, and it 50 will also be obvious that my invention is susceptible of some change and modification without departing from the principles and spirit thereof and for this reason I do not wish to be understood as limiting myself to the precise arrangement and formation of 55 the several parts herein shown in carrying out my invention in practice except as hereinafter claimed.

I claim:

60 1. A mechanism of the class described comprising, in combination, a cylinder adapted for communication with a source of gas under pressure, a pipe leading therefrom, a valve mounted within the cylinder, the pressure of the gas adapted to maintain

the valve beyond the connection between the cylinder and the pipe to permit unobstructed flow through the pipe, the stem on the valve extending exteriorly of the cylinder, a weighted member carried by said stem for 70 moving the valve into closed position upon reduction of the gas pressure, a latch pivotally engaged with the cylinder, said latch being disposed toward the stem and in a direction lengthwise thereof, said latch being provided with an inwardly facing shoulder, an outstanding pin carried by the stem, the latch outwardly of the shoulder having contact with the pin when the valve is in open position, the shoulder of the latch 75 engaging over the pin when the valve is in closed position to hold the valve against movement into open position, and means 80 constantly urging the latch toward the stem and pin.

2. A mechanism of the class described comprising, in combination, a cylinder adapted for communication with a source of gas under pressure, a pipe leading therefrom, a valve mounted within the cylinder, the pressure of the gas adapted to maintain 90 the valve beyond the connection between the cylinder and the pipe to permit unobstructed flow through the pipe, the stem on the valve extending exteriorly of the cylinder, a weighted member carried by said stem for moving the valve into closed position upon reduction of the gas pressure, an outstanding arm carried by the end portion 95 of the cylinder through which the stem extends, a latch pivotally engaged with said arm, said latch being disposed toward the stem and in a direction lengthwise thereof, said latch being provided with an inwardly facing shoulder, an outstanding pin carried by the stem, the latch outwardly of the shoulder having contact with the pin when the valve is in open position, the shoulder of the latch 100 engaging over the pin when the valve is in closed position to hold the valve against movement into open position, and means constantly urging the latch toward the stem and pin.

3. A mechanism of the class described comprising, in combination, a cylinder adapted for communication with a source of gas under pressure, a pipe leading therefrom, a valve mounted within the cylinder, the pressure of the gas adapted to maintain 110 the valve beyond the connection between the cylinder and the pipe to permit unobstructed flow through the pipe, the stem on the valve extending exteriorly of the cylinder, a weighted member carried by said stem for moving the valve into closed position 115 upon reduction of the gas pressure, a latch pivotally engaged with the cylinder, said latch being disposed toward the stem and in a direction lengthwise thereof, said latch being provided with an inwardly facing 120 shoulder, an outstanding pin carried by the stem, the latch outwardly of the shoulder having contact with the pin when the valve is in open position, the shoulder of the latch engaging over the pin when the valve is in closed position to hold the valve against movement into open position, and means constantly urging the latch toward the stem and pin.

125 4. A mechanism of the class described comprising, in combination, a cylinder adapted for communication with a source of gas under pressure, a pipe leading therefrom, a valve mounted within the cylinder, the pressure of the gas adapted to maintain 130

shoulder, an outstanding pin carried by the stem, the latch outwardly of the shoulder having contact with the pin when the valve is in open position, the shoulder of the latch constantly urging the latch toward the stem and pin, the portion of the latch outwardly of the shoulder being grooved to snugly engage the stem outwardly of the pin. 10

5 engaging over the pin when the valve is in closed position to hold the valve against movement into open position, and means

In testimony whereof I hereunto affix my signature.

ROBERT G. CAMBLIN.
